PLUMB BOB CARRIER

Edward S. Williams, New Philadelphia, Ohio

Application August 10, 1950, Serial No. 178,668

2 Claims. (Cl. 33—217)

1

The invention relates to new and useful improvements in carriers for plumb bobs, and more particularly to a carrier in the form of a housing or case containing a reel or spool upon which the plumb line is wound, and having a compartment therein to receive and house the plumb bob when not in use.

It is an object of the invention to provide such a device comprising a relatively flat, substantially rectangular housing having a reel or spool therein for winding up and paying out the plumb line, and a compartment in the housing for receiving and housing the plumb bob.

Another object is to provide a manually operated latch for locking the plumb bob within said compartment when not in use.

A further object is to so construct and arrange the parts that when the plumb line is reeled in the plumb bob will be drawn into its compartment to a position where the latch may be operated to retain the plumb bob therein.

A still further object is to provide the plumb bob with a reduced neck at its upper end, terminating in an enlarged head, the latch being in the form of a slideable member having a bifurcated end portion for engaging said reduced neck.

Another object is to provide an open-sided housing having a removable side wall upon which the reel is journaled.

A further object is to provide such a plumb bob carrier so constructed that plumbing from one surface to another surface above it may be accomplished accurately and quickly.

The above objects together with others which will be apparent from the drawing and following description, or which may be later referred to, may be attained by constructing the improved plumb bob carrier in the manner hereinafter described in detail and illustrated in the accompanying drawing, in which;

Figure 1 is a perspective view of a plumb bob carrier embodying the invention;

Fig. 2 an elevation showing the interior of the housing with the detachable side wall removed;

Fig. 3 an elevation of the inner side of the detachable side wall of the housing;

Fig. 4 a transverse section through the housing, taken as on the line 4—4, Fig. 2;

Fig. 5 an elevation showing the manner of plumbing from one surface to another surface above it; and,

Fig. 6 a detached, perspective view of the sliding latch for retaining the plumb bob within the housing.

2

Referring now more particularly to the embodiment of the invention illustrated in the drawing, in which similar numerals refer to similar parts throughout, the device includes a housing, indicated generally at 10, which may be molded or cast from plastic or other suitable material.

This housing is preferably open-sided, having the back wall 11 and an integral flange, indicated generally at 12, formed around its edges to provide end walls 13 and 14, a top wall 15 and bottom wall 16 which terminates at a point spaced from the end wall 13 so as to provide an opening 17 in the bottom of the housing, of sufficient size to permit the plumb bob to pass therethrough, an integral upright partition wall 18, parallel to the end wall 13, extending upward within the housing, from the terminal end of the bottom wall 16, so as to provide a compartment 19 within the housing, into which the plumb bob may be received when not in use, as will be later described.

The upper corners of the housing may be rounded, as indicated at 20 and 21, and bosses 22 may be formed integrally with the flange 12 and back wall 11 at the upper corner 20, in the lower corner directly therebeneath and at the junction of the bottom wall 16 and partition wall 18, these bosses being provided with tapped openings 23 for a purpose to be later described.

30 A post 24, having a peripheral groove 25, may be formed integrally with the back wall 11 of the housing and is preferably provided with a tapped opening 26. This post is located above the center of the compartment 19.

35 The front wall 27 of the housing is preferably formed separable and is of the same outline as the housing and adapted to be connected to the housing by means of screws 28, located through suitable apertures 29 in the front wall 27 and 40 engaged in the threaded openings 23 and 26 of the housing.

The reel 30 is carried by the removable front wall 27 of the housing. For this purpose one trunnion 31 of the reel is located through a suitable aperture 32 in the front wall 27 and the crank handle 33 is attached to the outer end of this trunnion as by the screw 34 engaged in the threaded aperture 35 in the trunnion 31.

The reel is thus journaled upon the front wall 27. The other end of the reel is provided with a similar trunnion 36 which may be received in an aperture 37 in the back wall 11 of the housing.

50 The plumb line 38 is adapted to be coiled upon the reel 30, as indicated at 39, and the end thereof passes through a slot 40 in the sliding latch

member 41, then through the groove 25 in the post 24, and is connected to the upper end of the plumb bob 42.

The sliding latch member 41 has the bifurcated, horizontal lower end 43, adapted to receive the reduced neck 44 of the plumb bob so that the enlarged head 45 thereof rests upon this bifurcated portion of the latch, when the plumb bob is withdrawn into the housing as shown in Fig. 2.

For the purpose of manually operating the sliding latch 41, the upper end thereof is rearwardly bent, in horizontal position, as indicated at 46, and may be connected to the finger button 47, as by the screw 48 located through the elongated slot 49 in the top wall 15 of the housing.

When the sliding latch member 41 is moved rearwardly from the position shown in Fig. 2, the bifurcated end 43 thereof is withdrawn from engagement with the plumb bob, permitting the same to descend from the housing by gravity as the plumb line 38 is paid off from the reel 30.

In order to prevent too rapid descent of the plumb bob, when the latch is released, the crank handle 33 may be manually operated to pay out the plumb line at the desired speed.

In order to accurately and quickly plumb from one surface to another surface above it, the housing may be positioned as shown in Fig. 5, against a ceiling or other upper surface, indicated at C, and mark may be made upon said upper surface, at the point where the upper corner of the housing contacts the surface, as indicated at U. This point U will then be directly above the center of the plumb bob 42 as it is allowed to descend.

From the above it will be evident that a simple, inexpensive and efficient plumb bob carrier is provided, having a reel therein for coiling the plumb line thereon, with a compartment within the housing for receiving and housing the plumb bob, when not in use, and means for retaining the plumb bob within this compartment so that the carrier may be handled or transported without danger of the reel unwinding.

I claim:

1. A plumb bob carrier comprising a relatively flat, substantially rectangular housing having an opening at one lower corner, a partition wall adjacent to said opening and extending upward within the housing to a point spaced from the top thereof forming an open ended compartment within the housing, a reel journaled within the housing between said partition wall and the opposite edge of the housing, a crank handle ex-

terior of the housing for operating said reel, a transverse post in the housing centrally located above the upper open end of said compartment, a plumb line coiled upon the reel and located over said transverse post, a plumb bob connected to the end of the plumb line and adapted to be withdrawn through said opening into the compartment and entirely within the housing, an enlarged head upon the top of the plumb bob, a latch member slidably mounted upon the top wall of the housing and having a depending portion terminating in a bifurcated end for engaging under said enlarged head to hold the plumb bob entirely within the housing, and means upon the exterior of the housing for operating the slideable latch member.

2. A plumb bob carrier comprising a relatively flat, substantially rectangular housing having an opening at one lower corner, a partition wall adjacent to said opening and extending upward within the housing to a point spaced from the top thereof forming an open ended compartment within the housing, a reel journaled within the housing between said partition wall and the opposite edge of the housing, a crank handle exterior of the housing for operating said reel, a transverse post in the housing centrally located above the upper open end of said compartment, a plumb line coiled upon the reel and located over said transverse post, a plumb bob connected to the end of the plumb line and adapted to be withdrawn through said opening into the compartment and entirely within the housing, an enlarged head upon the top of the plumb bob, a latch member slidably mounted upon the top wall of the housing and having a depending portion terminating in a bifurcated end for engaging under said enlarged head to hold the plumb bob entirely within the housing, there being an aperture in the depending portion of the slideable latch member through which the plumb line is located, and means upon the exterior of the housing for operating the slideable latch member.

EDWARD S. WILLIAMS.
